FORD W. HARRIS, OF WILKINSBURG, PENNSYLVANIA, ASSIGNOR TO WESTINGHOUSE ELECTRIC AND MANUFACTURING COMPANY, A CORPORATION OF PENNSYLVANIA.

CIRCUIT-BREAKER.

1,113,335.

Specification of Letters Patent. Patented Oct. 13, 1914.

Application filed August 6, 1910. Serial No. 575,999.

To all whom it may concern:

Be it known that I, FORD W. HARRIS, a citizen of the United States, and a resident of Wilkinsburg, in the county of Allegheny 5 and State of Pennsylvania, have invented a new and useful Improvement in Circuit-Breakers, of which the following is a specification.

My invention relates to automatic circuit-breakers, and it has for its object to provide a simple and reliable calibration device whereby a circuit-breaker may be adjusted to interrupt the circuit under predetermined conditions.

Figure 1 of the accompanying drawings is a side elevation of a circuit-breaker which embodies my invention, a portion being broken away. Fig. 2 is a front view of a portion of the mechanism shown in Fig. 1, 20 and Fig. 3 is a sectional view, on the line III--III of Fig. 1.

Referring to the drawings, the circuit-breaker comprises an insulating slab or panel 1, stationary contact terminals 2 and 3, a movable contact member 4, an operating mechanism 5, a release magnet 6, a tripping mechanism 7, and a calibration device 8.

The stationary contact member 2 comprises a copper block 2^a, an auxiliary copper contact terminal 2^b, and a carbon arcing contact terminal 2^c. The contact block 2^a forms the head of a terminal stud 10^a which projects through a hole in the insulating panel 1 and is secured in position by a nut 2^a. The carbon arcing tip 2^c is fitted securely into its retaining member 11 which is pivotally mounted between the side arms of an U-shaped bracket 9 by means of a pin 10, 35 said bracket being held in position by a screw 19^a which also secures auxiliary contact terminal 2^b and spring 14 in position. The spring 14 is adapted to press against the arcing tip 2^c and maintain it in engagement with its cooperating arcing tip 27 when the breaker is closed.

Stationary contact terminal 3 comprises a heavy copper strap or plate 16 which is secured, at its lower end, to the head 17 of 50 a stud 18, which forms the other terminal of the breaker. The upper end of the strap 16 is fastened to the insulating panel 1 by means of screws (not shown), a spacing block 19 being interposed to provide suffi-

cient room to accommodate the core of the 55 release magnet 6.

The movable contact member 4 comprises an U-shaped casting 22 pivoted, at its lower end, on a stud 23, which is mounted in two main supporting brackets 24 and 25. The 60 free end of the casting 22 is provided with a spring-supported auxiliary contact member 26 and a similarly connected arcing contact member 27, said contact members being respectively adapted to coöperate with the 65 stationary contact members 2^b and 2^c. A main bridging contact member 28 is composed of copper strips held in position by curved clamping blocks 29 and 30, and is pivotally supported in the U-shaped casting 22 by means of a pin 34 and a lug 33, the latter being an integral part of the outer clamping block 30. The contact member, thus supported, is adapted to bridge across the main stationary terminals 3 and 2^a to 75 establish the connections of the electric circuit.

The completion of the shunt circuit through the auxiliary contact members and their resilient supports is accomplished by 80 a copper spring 36 which is secured to a web 37, cast on the inside of the U-shaped member 22, and is adapted to engage stationary terminal 3, being bent to conform to the circular outline of the pivoted end of the movable contact member.

The arrangement and proportions of the several contact terminals comprising the movable contact member 4 are such that, as the breaker is released, the main contact 90 member 28, the auxiliary contact member 26 and the carbon arcing tip 27 open successively to confine the final break and resulting arc to the carbon arcing tip.

The operating mechanism of the breaker 95 comprises an operating lever 40 fulcrumed on a pin 41 between the main supporting brackets 24 and 25, a connecting link 42, an equalizing member 43 and a spring 44. The operating lever 40 is provided with a retaining pin or catch 47 and a stop 48 to engage the supporting bracket 24 and limit movement in a clockwise direction. The operating lever 40 is also provided with a handle 49, at its outer end, and with a spring 50 105 which is secured to the operating lever by a pin 51 and to a lug 52 on the main supporting bracket. The tension of the spring

50 is exerted to collapse the toggle formed by the arm 39 of the operating lever and the connecting link 42, when the latch 54 is released.

5 Equalizing member 43 is contained within the U-shaped casting 22, one end being pivotally secured to said casting by a pin 34 while the other end is acted upon by spring 44. Spring 44 is held in position 10 between the equalizing link and the block 38, by means of projections 57 and 58, a stop 59 being provided to restrict the movement of said link in a counter-clockwise direction. The connecting link 42 is pivotally secured 15 to the equalizing member 43 by a pin 60 which is located between the ends of said member but nearer to its pivoted end.

The release magnet 6 comprises an U-shaped core member 61 supported on bosses 20 62 and 63 between the main bracket members 24 and 25, a magnetizing coil of a single turn in the form of the copper strap 16, which is located between the arms of said core, and a pivotally mounted armature 25 64. The armature 64 is supported upon a shaft 65 and embodies a weighted portion 76, and main arms 66 and 66^a connected by a thin web 67 which is recessed at 68 to accommodate a tripping lever 69. When 30 sufficiently energized, the armature 64 is attracted by the core member 61 and makes contact with said core member on its inclined faces 72 and 73, the pin 74 serving to maintain a slight air-gap to overcome 35 the tendency of the core members to stick together. Sufficient weight is placed in the lower portion 76 of the armature to insure its separation from the core 61 when the magnetizing force is discontinued.

40 The tripping mechanism of the breaker comprises a latch 54, which engages the retaining pin 47 when the breaker is closed, a tripping member 80 and the armature 64. The latch 54 is pivoted on a pin 81, which 45 projects through extensions 82 and 83 of the main supporting brackets 24 and 25. In order to limit the movement of the latch 54, a pin 84 is located in a slot 85 which is provided at the inner end of the latch, and 50 this pin also serves as a stop for a spring 86, which projects beneath the latch 54 and maintains it in its normal position. The upper portion of the bent tripping member 80 has arms 88 and 89, said arms being provided with downward extensions 90 and 91, which straddle the latch 54 and through which said member is pivotally supported by the pin 81. The outer end of the member 80 forms a trigger 93 which is provided with 55 an adjustable screw 94 to engage the latch 54. At the inner end of the tripping member, the two arms 88 and 89 merge into a single rod 69, and shoulders 99 and 100 are provided to engage the web 67 of the magnet 60 armature as said armature is attracted to its 65

core. The lower portion of the rod 69 forms a button 104 which is readily accessible through an opening 105 in the bottom plate 106 of the breaker frame.

The calibration device comprises an inclined plate 108 which is adjustably secured to the main arms 66 and 66^a of the armature 64 by means of slots 110 and 111 and screws 112 and 113, a rotatable member 117 pinned to a shaft 115 and provided with one convolution of a helix 120 of great pitch, the axis of the helical member and the edge of the plate being in the same plane, but at an angle to each other, cylindrical calibrated disk 118 provided with an opening or window 121 in the front plate 122 of the breaker frame, and an adjusting knob 119.

The calibration plate 108 rests upon the periphery of the helix 120, and the position of the point of contact between said plate 85 and helix is varied by the adjusting knob 119. It will be readily understood that, as the helix is turned by right-hand rotation of the adjusting knob, the point of contact between the plate and the helix travels to the left, thus raising the plate and consequently effecting a decrease in the length of the air-gap between the armature 64 and the core member 61. By thus varying the point of contact, the length of air-gap may 90 be adjusted to correspond to any predetermined current value desired, within the range of adjustment obtainable. The angle of inclination of the calibration plate is the controlling feature which determines the 95 maximum and minimum current adjustments which may be secured for a given setting of the plate. If the angle between the plate and the axis of the helical member is made very slight, only a narrow range of 100 adjustment is possible, while any increase in the angle of inclination results in correspondingly wider limits of adjustment.

The preliminary setting of the calibration plate is as follows: Suppose, for instance, 110 that a range of adjustments between two hundred and a thousand amperes, is desired, as is the case with the breaker illustrated, the adjusting knob is first turned until the point of contact between the plate and helix 115 is at its extreme left position. The setting of the left end of the plate is then adjusted until actual test trips the breaker at two hundred amperes. The point of contact is then changed to its extreme right position and the right end of the plate is adjusted until the breaker trips at one thousand amperes on actual test. With the two extreme settings determined, intermediate adjustments are secured by varying the point 120 of contact along the plate by means of the adjusting knob. Having once set the plate for a particular range of adjustments, the calibration disk 118 is graduated correspondingly in amperes so that, to adjust the 125 130

breaker to trip at any predetermined amount of current traversing the circuit, it is only necessary to turn the adjusting knob until the required figure on the disk is seen 5 through the window 121 opposite the arrow 123.

The operation of the breaker is as follows: Assuming that the breaker is closed, the various parts occupying the positions shown in 10 the drawings, the breaker may be released either manually or automatically. In order to trip the breaker by the hand of the operator, it is only necessary to insert a finger through the opening 105 and press upward 15 upon the tripping rod 69 to cause the trigger 93 to release the latch 54 by means of the adjusting screw 94, whereupon the springs 56 and 44 act in conjunction to collapse the toggle formed by the operating lever 40 20 and the connecting link 42, and cause the breaker to open and the electric circuit to be broken. In the event of automatic operation a predetermined amount of current through the breaker actuates the armature 54, and the web 67 engages the shoulders 99 25 and 100 of the tripping member and causes the latch 54 to be released and the breaker to open as hereinbefore described. In order to close the breaker, the operating lever 40 30 is forced to its lowest position by means of the handle 49, thus forcing the toggle nearly to its dead center and, consequently, exerting a considerable pressure upon the equalizing member 43 which closes the contact 35 members. The breaker is held in its closed position by means of the latch 54, which engages the retaining pin 47 when the operating handle is in its lowest position.

While I have described and illustrated a 40 specific structure, I desire that variation in size and arrangement of parts may be effected which do not depart from the spirit and scope of my invention, and I further desire that only such limitations shall be imposed 45 as are indicated in the appended claims.

I claim as my invention:

1. The combination with a magnetizable core comprising a stationary portion and a movable portion, and a magnetizing coil for 50 said core, of a rotatable member provided with one convolution of a helical thread of great pitch, and a supporting plate adjustably secured to the movable core member

and adapted to rest upon the periphery of the helical thread, the edge of the plate and 55 the axis of said helical member being in the same plane but non-parallel.

2. The combination with a magnetizable core comprising a stationary portion and a 60 pivotally supported movable portion, and a magnetizing coil for said core, of a rotatable helical cam and an inclined plate 65 adjustably secured to the movable core member and adapted to rest upon the periphery of the rotatable helical cam, the air-gap between the core members being dependent upon the position of the point of contact between said inclined plate and said cam helix.

3. In a circuit interrupter, the combination 70 with a stationary core, a pivotally mounted movable armature, and a magnetizing coil, of a supporting plate adjustably secured at each end to the free end of the movable armature by means of a screw and slot, of a rotatable helical cam member upon which the edge of said bearing plate 75 rests, the edge of the plate and the axis of the cam member being in the same plane but non-parallel.

4. In a circuit interrupter, the combination 80 with a tripping magnet comprising a stationary core, a magnetizing coil therefor and a pivotally supported movable armature, of a rotatable helical cam member, and 85 a plate adjustably secured to the free end of said movable armature and having an inclined edge to be engaged by said cam member.

5. The combination with a release magnet 90 for circuit interrupters comprising a stationary core, a magnetizing coil therefor and a movable armature provided with an attachment having an inclined surface, of a helical cam member adapted to engage said 95 inclined surface to adjust the interrupter to trip at any predetermined amount of current.

In testimony whereof, I have hereunto 100 subscribed my name this 28th day of July, 1910.

FORD W. HARRIS.
